UNITED STATES PATENT OFFICE

WILLIAM M. SHEEHAN, OF ST. LOUIS, MISSOURI, ASSIGNOR, BY MESNE ASSIGNMENTS, TO GENERAL STEEL CASTINGS CORPORATION, OF GRANITE CITY, ILLINOIS, A CORPORATION OF DELAWARE

RAILWAY-LOCOMOTIVE STRUCTURE

Application filed March 18, 1928. Serial No. 262,070.

My invention relates to railway rolling stock and consists in novel construction of various features of vehicles frame structure and is particularly adapted for use in locomotive underframing in which all, or a substantial part, of the framing is formed integrally. Some of the features of my invention are particularly adapted for use on locomotives and I illustrate such embodiment 10 of my invention in the accompanying drawings.

One of the objects of my invention is to provide an improved center plate construction and to unite the same with the boiler 15 saddle and adjacent parts of the locomotive, preferably in a one-piece casting.

Another object of my invention is to provide an improved front deck structure adapted to mount the pumps for air and feed water 20 with a minimum number of fastening devices and in such a manner that the pumps will be protected from injury by foreign articles, which may collide with the locomotive, and also to afford such pumps protection from air currents.

Another object of my invention is to provide locomotive framing with suitable means for cooperating with a lateral motion driving box device whereby the movement of the 30 box may be adjusted with a minimum amount of delay and labor.

Other detailed objects of my invention are set forth in my specification and will be readily understood by reference to the accompanying drawings in which—

Figure 1 is a top view of the forward portion of the locomotive frame, a part of the same being broken away to avoid duplication.

Figure 2 is a side elevation of the parts illustrated in Figure 1.

Figure 3 is a vertical longitudinal section taken on line 3—3 of Figure 1.

Figure 4 is a horizontal section taken on line 4—4 of Figure 2.

Figures 5 and 6 are vertical transverse sections taken on lines 5—5 and 6—6 of Figure 1.

Figure 7 is a detail vertical transverse section taken on line 7—7 of Figure 4.

Figure 8 is an elevation of a detail of the

lateral motion adjustment structure illustrated in Figure 7.

Figure 9 is a fragmentary plan view illustrating a modified form of my invention.

Figure 10 is a side elevation of the same.

Figure 11 is a vertical transverse section taken on line 11—11 of Figure 9.

Figure 12 is a detail section through a modified center plate structure.

My invention is shown as being embodied in a locomotive bed of the one-piece type in which side frame elements 1 have formed integrally therewith other elements such as the steam cylinders 2, the steam control valve chambers 3, the boiler saddle 4, the front deck plate 5, and pedestal jaws 6.

Formed integrally with the steam cylinders and the boiler saddle are inwardly and downwardly projecting elements 7 carrying between them a downwardly projecting circular dowel-like member 8 which forms the body of the locomotive center plate but is provided with a renewable cup-shaped wear plate 9 adapted to fit into the corresponding center plate member 10 of the truck 11 (see Figure 75 3). The usual construction is to provide a separate center plate on underside of cylinder casting which casting is bolted to the frame member and on account of the height of the cylinder casting, a deep center plate member is necessary. The structure shown eliminates the necessity of providing a deep center plate and there are no bolts to be kept tight or other difficulty accompanying the attachment of a center plate to the locomotive 85 framing. Preferably, the wear plate 9 is secured to the dowel member 8 by spot-welding, as indicated at W.

The front deck 5 is provided with upstanding brackets 12 and 13 adapted to mount 90 pumps such as the air pumps indicated at 14 or the feed water pumps indicated at 15. It will be noted that the rear ends 16 of these brackets merge with the inwardly extending front walls 17 of the cylinder and cylinder valve structure whereby the brackets 12 and 13 are braced for a substantial distance above the front deck. Suitable brackets 18 for mounting or bracing a pilot beam 19 (which may be formed integrally with the front deck 100

or applied thereto) are formed integrally with the deck and are extended upwardly, as indicated at 20, in front of the space occupied by the pumps 14 and 15, and serve to protect the latter against any object which may be struck by the locomotive and also serve to deflect air currents from the pumps which is desirable, particularly in cold weather.

Adjacent to the pedestal jaw 6 the sides 1 of 10 the bed are connected by integral cross ties 21 and each of these ties 21 is provided with a flange 22 adapted to mount a wear plate 23 against which may bear the vertical arm 24 of a bell crank lever mounted on a driving box 15 25 and carrying the spring saddle 26. The mounting of the spring saddle on the driving box does not form part of my invention.

The contacting faces of the flange 22 and the wear plate 23 are provided with interengaging elements such as the lip 27 and the adjacent edge of the wear plate, whereby relative rotation of the wear plate and flange is prevented. The wear plate is retained in position upon flange 22 by means of the trunnion-like element 28, having a threaded inner end and retaining nuts 29. I prefer to provide a suitable shim 30 between plate 23 and flange 22 and, by use of shims of different thickness, it will be possible to adjust the normal lateral movement of the driving box. Such adjustment can be readily made with the U-shaped shim detailed in Figure 8 by loosening nuts 29 and lowering the shim and inserting a new shim which is thicker or thinner than the one removed. It will be noted that such adjustment can be made from below and does not require the disassembly of any other elements of the device and does not require the machining of any part of the lateral motion device, such as has been required in previous structures.

In Figures 9 to 11, I illustrate a modification of my invention in which the bed 31 is provided with finished pads 32 on its sides 45 whereby cylinders may be bolted to the bed in the usual manner. It will be noted that this does not change the desirable features of the center plate dowel member 35 which is shown as being constructed like the corresponding member of the preferred form of my invention.

In Figure 12 I illustrate a modified arrangement of a renewable wear plate 33 which is here shown as an annular ring surrounding the dowel member 34 but not covering the bottom of member 34. This will be preferable in some types of construction and may be used, if desired. The plate 33 is prevented against rotation on member 34 by 60 means of spot-welding or by other suitable means such as referred to in my copending application Serial Number 270,950, filed April 18, 1928.

In each of the forms of my center plate 65 structure the dowel member and wear plate

are arranged to permit free passage therethrough of the center pin so that the same may be inserted or removed in the usual manner. This is provided for by the enlarged opening indicated at X.

It is also to be understood that the above arrangement of dowel member and wear plate can be used for other railway vehicle underframes than locomotive underframes.

Other variations in the details of my invention may be made without departing from the spirit thereof and I contemplate the exclusive use of such modifications as come within the scope of my claims.

I claim:

1. A railway vehicle frame member having an integral downward projection adapted to fit a truck center plate member, and a renewable element surrounding the outer periphery of said projection for contact with the inner periphery of said truck member.

2. A railway vehicle frame member having an integral downward projection adapted to fit a truck center plate member, a renewable element surrounding the outer periphery of said projection for contact with the inner periphery of said truck member, and means spaced from said peripheries for preventing rotation of said element on said projection.

3. In a railway vehicle frame member having an integral downward projection adapted to fit a truck center plate member, a cup shaped renewable member fitting over the lower end of said projection and provided with upstanding elements for contact with the outside of said projection and with the inside of said truck member, and means spaced from said elements preventing rotation of said element on said projection.

4. In a railway vehicle frame member having an integral downward cylindrical projection adapted to fit a cylindrical truck center plate member, and a cup shaped renewable member surrounding the lower end of said projection and having a cylindrical wall for insertion between said projection and said truck member, there being a central opening in said projection and element for receiving a center pin.

5. A locomotive front deck plate provided with an integral bracket for mounting a pump.

6. A locomotive front deck plate provided on opposite sides with brackets for air and feed water pumps respectively.

7. A one-piece casting comprising a front deck of a locomotive and provided with an upstanding bracket for mounting a pump.

8. A one-piece casting comprising a front deck of a locomotive and provided with an upstanding bracket for mounting a pump and including a flange for protecting a pump mounted thereon.

9. In a locomotive casting, a boiler saddle,

a steam cylinder, a wall connecting said cylinder and saddle, a front deck plate, and an upstanding bracket on said plate merging with said wall.

5 10. In a locomotive casting, a front deck plate including an outwardly extending pilot beam bracket, a pump bracket extending upwardly from said deck plate from behind said pilot beam bracket, and a pump 10 10 protecting flange projecting upwardly from said pilot beam bracket and outwardly from said pump bracket.

11. A one-piece locomotive bed casting comprising a boiler saddle, a front deck 15 plate, steam cylinders, air pump bracket, and a feed water pump bracket, all formed integrally.

12. A one-piece locomotive bed casting comprising a boiler saddle, a front deck plate, 20 steam cylinders, air pump bracket, a feed water pump bracket, a pilot beam bracket, and pump protecting plates in front of said pump brackets all formed integrally.

13. In a locomotive, pedestal jaws, adapted 25 to receive a driving box between them, a frame element adjacent to one of said jaws, a wear plate for a driving box lateral motion device mounted on said element, and means for moving said plate in a horizontal 30 line for adjusting said plate transversely of the locomotive.

14. In a locomotive, pedestal jaws, adapted to receive a driving box between them, a frame element adjacent to one of said jaws, 35 a wear plate for a driving box lateral motion device mounted on said element, and means on said plate extending through said element for adjusting said plate transversely of the locomotive.

40 15. In a locomotive, pedestal jaws, adapted to receive a driving box between them, a frame element adjacent to one of said jaws, a wear plate for a driving box lateral motion device provided with a trunnion-like 45 member passing through said element and having a retaining nut, and a replaceable shim between said plate and element.

16. In a locomotive, pedestal jaws, adapted 50 to receive a driving box between them, a frame element adjacent to one of said jaws, a wear plate for a driving box lateral motion device provided with a trunnion-like member passing through said element and having a retaining nut, and a replaceable shim between said plate and element, said shim being removable from and applicable to said plate and flange from below the same.

55 17. In a locomotive, a pedestal element, a cross tie integral therewith, a flange on said cross tie, and a wear plate for a driving box lateral motion device adjustably mounted on said flange.

18. In a locomotive, a pedestal element, a cross tie integral therewith, a flange on said 60 cross tie, a wear plate for a driving box lat-

eral motion device applied to said flange, and detachable means for holding said plate in position.

19. In a locomotive, a pedestal element, a cross tie integral therewith, a flange on said cross tie, a wear plate for a driving box lateral motion device applied to said flange, there being interengaging elements on said flange and plate to prevent their relative rotation, and means for holding said plate on said flange. 75

20. In a locomotive casting, a longitudinal side frame member adapted to be located near the front end of the locomotive, and an integral bracket on said member for mounting a pump. 80

21. A one-piece locomotive casting comprising a longitudinal side member adapted to be located near the front end of the locomotive, a bracket on said member for mounting a pump, and an element for protecting a pump mounted on said bracket. 85

22. In a locomotive casting, a boiler saddle, a side frame member projecting forwardly from said saddle, an upstanding bracket on said member, the vertical wall of said bracket merging with the outer wall of said saddle. 90

23. In a locomotive, a pedestal element, a crosstie on the inside of said pedestal and below the level of the top of the pedestal opening, a flange on said crosstie, a wear plate for a driving box lateral motion device applied to said flange, there being interengaging elements on said flange and plate to prevent their relative rotation, and means for holding said plate on said flange. 95 100

24. In a locomotive, a pedestal element, a crosstie extending inwardly from said pedestal and below the level of the top of the pedestal opening and having a vertical surface spaced from said pedestal, a wear plate for a driving box lateral motion device applied to said surface, and means on said plate and said crosstie for holding said plate in position. 105 110

25. In a locomotive, a pedestal element, a crosstie extending inwardly from said pedestal and having a vertical surface spaced from said pedestal, a wear plate for a driving box lateral motion device applied to said surface, means on said plate and said crosstie for holding said plate in position, and means between said plate and surface to provide for lateral adjustment of said plate. 115

26. In a railway vehicle, a body center plate member, and a cup-shaped renewable member fitting over the lower portion of said center plate member and having upstanding sides for transferring lateral thrusts directly between the periphery of said member and the interior of a truck center plate. 120 125

27. A railway vehicle frame member having an integral downward projection adapted to fit a truck center plate member, and a cup shaped renewable element surrounding the 130

outer periphery of said projection for contact
with the inner periphery of said truck mem-
ber.

In testimony whereof I hereunto affix my
signature this 28th day of February, 1928.

WILLIAM M. SHEEHAN.
